UNITED STATES PATENT OFFICE.

MARTIN PRIOR BOSS, OF SAN FRANCISCO, CALIFORNIA.

GRINDING-PAN.

SPECIFICATION forming part of Letters Patent No. 398,936, dated March 5, 1889.

Application filed May 4, 1888. Serial No. 272,822. (No model.)

To all whom it may concern:

Be it known that I, MARTIN PRIOR BOSS, of the city and county of San Francisco, and State of California, have invented an Improvement in Grinding-Pans; and I hereby declare the following to be a full, clear, and exact description thereof.

My invention relates to that class of pans for grinding ore in which a muller rotates within the pan and crushes the ore between its shoes and the dies of the pan; and my invention consists in the constructions and combinations of devices which I shall hereinafter fully describe and claim.

Referring to the accompanying drawings, Figure 1 is a vertical section of my grinding-pan. Fig. 2 is a top view of the shoe. Fig. 3 is a top view of the die. Fig. 4 is a section of a part of the shoe and die through the slots *c* and *b* on the line *y y* of Figs. 2 and 3. Fig. 5 is a section of the lug *c'* on the shoe *C* through the line *z z* on Fig. 2.

A is the pan, having an opening, *a*, in the base of its rim, no plug being used as in ordinary pans.

B is the die in the pan.

C is the shoe of the muller.

D is the muller, the driver or stem *d* of which extends upwardly, and is secured to the drive-shaft *E* in suitable manner, as by a feather or feathers, so that it may be rotated by said shaft, but may still have a vertical movement for raising or lowering its shoe.

F is a driver-cap resting on top of the muller driver or stem, and connected therewith by bolts *f*, which are secured at their lower ends to the muller-driver stem, and their upper ends, passing through the sides of the cap, have securing-nuts *f'*. Within the cap is a nut, *G*. Its upper end passes through the top of the cap and receives a nut, *g*, so that said nut may move up and down in the cap.

H is the adjusting-screw, which passes down through the nut *G* and has its lower end bearing on the top of the drive-shaft *E*.

I is a spring located within the driver-cap *F* and around the nut *G*. Its base bears on the flanged base of the nut and its top bears up under the flanged top of the cap.

It will be seen that in order to raise the

muller the screw *H* is turned down, so that the nut *G* moves up and through the spring *I* raises the driver-cap *F* and muller driver or stem *d*. The reverse movement of the screw *H* allows the muller to move down. The spring, therefore, receives the thrust of the screw to adjust the muller. By these means, as before mentioned, the pressure or weight of the shoe while grinding is regulated at will to increase or decrease the feed, as well as to determine the fineness of the grinding.

The die *B* in the pan is a ring or annular die, and in its inner surface are made the inclined grooves *b*, which, instead of extending all the way across the die, as do the intervening passages in the dies of the ordinary pan, terminate at a short distance from the inner surface.

The shoe *C* of the muller is a ring or annular shoe, and in its inner surface are made the inclined grooves *c*, of a character similar to the grooves *b* of the die and similarly located—that is to say, they do not extend all the way across the shoe.

The muller *D* is an annular one, having a solid body connected with its central stem, *d*, by arms *d'*, and it has an inwardly-turned flange, *d''*, at its top. It is connected with the shoe *C* by means of bolts *d''*, the heads of which are confined in grooved lugs *c'* on the shoe, and their ends pass through ears *d''* on the muller and receive nuts *d''*, as shown. A tight joint is formed between the foot of the muller and its shoe by the intervention of a packing-ring or gasket, *J*.

The pulp is fed into the center of the muller, and is confined therein. It thence passes down and is directed by the inclined grooves *c b* to and between the shoe and die, and thence, being ground, passes directly out of the pan through the opening *a*. It will be seen that this is the only course open for the pulp. It can pass out in no other way but between the shoe and die, and therefore every bit of it is once subjected to the grinding action, and once only.

In many of the ordinary pans the pulp is fed into and fills the pan itself, and some portions may pass between the shoes and dies many times before other portions are subjected

to the grinding action at all; but in my pan the shape of the muller so confines and directs the pulp that it has to follow the course described, and every bit of it is ground successively in its passage to the discharge.

Having thus described my invention, what I claim as new, and desire to secure by Letters Patent, is—

1. In a grinding-pan, a muller having the stem d , and the drive-shaft E, passing into said stem and adjustably connected therewith, whereby the muller is rotated and is adapted to move vertically, in combination with the driver-cap F, secured to the top of the muller-
15 stem and having a flanged top, the adjusting-screw H, passing into the driver-cap and having its lower end bearing on the top of the drive-shaft, the nut G within the driver-cap and seated on the adjusting-screw, said nut
20 having a flanged base, and the spring I within the driver-cap, around the nut, and bearing between the flanged base of said nut and the flanged top of said driver-cap, substantially as herein described.

2. In a grinding-pan, the combination of a 25 pan, a drive-shaft and operative mechanism therefor, a die, a centrally-apertured shoe, and a muller having an apertured annular body and inwardly-curved flange d^2 , for confining and directing the pulp between the shoe and 30 die, substantially as herein described.

3. In a grinding-pan, and in combination with the pan having a die in its bottom and a discharge-opening in the base of its rim, the annular muller for confining the pulp, and 35 having a centrally-apertured shoe on its foot operating over the die for directing the pulp outwardly between the shoe and die to the discharge-opening, said muller having an inwardly-curved flange, d^2 , substantially as de- 40 scribed.

In witness whereof I have hereunto set my hand.

MARTIN PRIOR BOSS.
